PORTABLE SEAT

Filed Dec. 23, 1935

UNITED STATES PATENT OFFICE

2,108,531

PORTABLE SEAT

William E. Flanders, Detroit, Mich.

Application December 23, 1935, Serial No. 55,692

1 Claim. (Cl. 155—133)

This invention relates to portable seats, and has particular reference to a collapsible chair adapted to be used at sporting events, at the beach, and on other occasions.

5 An object of the invention is the provision of a device which may be used in cooperation with ordinary "bleacher seats" to form a comfortable seat and to support the user's back.

Another object of the invention is the provision 10 of a device of the character referred to which is easily collapsible and foldable into a compact and lightweight bundle which may be readily carried about.

Still another object of the invention is the provision 15 of a device which may be adapted to be used upon the ground or at the beach to form a comfortable seat.

A further object of the invention is the provision 20 of a device which will protect the user's clothes from becoming soiled by sitting upon dirty "bleacher seats" or upon the ground.

Other objects and advantages of the invention will appear as the description proceeds.

The invention resides in the improved construction 25 of the portable seat, and in the combination and arrangement of parts, the novelty of which will be particularly pointed out and distinctly claimed hereinafter.

In the accompanying drawing, which constitutes 30 part of my disclosure, I have fully and clearly illustrated a preferred embodiment of the invention, in which drawing:

Fig. 1 is a perspective view of my portable seat being used in conjunction with an ordinary 35 "bleacher seat"; and

Fig. 2 is a side elevation of the device shown in Fig. 1, but adjusted to be used on the beach or upon the ground.

Referring now more particularly to the drawing, it will be seen that in the embodiment herein disclosed, my device is extremely simple in construction and comprises the base members 10, the side members 11 and the supporting arms 12. For the sake of strength and compactness, I prefer to construct the members 10, 11, and 12 of short tubular pieces, which may be chrome or otherwise suitably plated to present an attractive appearance. However, the above mentioned members may be made of any suitable material 50 and also in other shapes.

The base members 10 are bent downwardly and rearwardly at their front ends to form the hook-like extensions 13, the latter being adapted to engage the front edge of the bleacher seat 14 (Fig. 1) to hold the portable seat in place. The

hooks 13 should be large enough to permit the engagement of various thickness of material to render the device universally applicable to all "bleacher seats" and the like. The rear ends of the base members 10 are drilled to accommodate 5 the rivets 15 which secure the members 10 to the side members 11. This construction permits the rivets 15 to act as pivots to enable the members 10 and 11 to be folded together. Intermediate the ends of the base members 10 are positioned 10 the loops 16 which are adjustably secured in place by means of rivets 16a which pass through holes in the members 10.

The aforesaid loops 16 are arranged to engage the hook-shaped lower ends 17 of the supporting 15 members 12 to hold the side members 11 in the proper relative position with the base members 10 to form a comfortable seat. The loops 16 are made large enough to permit the insertion of the hooks 17 therethrough. The upper ends 18 of the 20 supporting arms 12 are pivotally secured to the side members 11 by means of the rivets 19 to enable them to be folded compactly together for carrying purposes.

Lateral support for the portable seat is provided by the two horizontal bars 20 and 21 which are pivotally secured at their outer ends to the upper extremities of the side members 11 by the rivets 22. The inner ends of the bars 20 and 21 are connected by means of the hinge 23 which 25 allows them to fold downwardly to enable the entire seat to be packed into a compact bundle. To prevent the seat from collapsing when in use, the bars 20 and 21 are fastened together by any 30 suitable attachment such as the hook 24 and the eye 25.

The back and the bottom of the portable seat are covered by the fabric pieces 26 and 27 respectively, which may be made of any satisfactory material and which are sewed or otherwise suitably secured to the side members 11 and to the base members 10. The fabric piece 26, which forms the back rest of the seat, is cut with the two upper strips 28 which are sewed around the horizontal bars 20 and 21. The loops thus formed 40 around the aforesaid bars are free to move along the bars to prevent binding and tearing of the material when the seat is folded. The fabric piece 27 which forms the base of the seat is cut 45 as at 29 (Fig. 1) to permit unobstructed operation of the hooks 17 and the rings 16.

An advantageous feature of my invention resides in the ease with which the portable seat may be adapted to serve either as an auxiliary bleacher seat or as a ground or beach seat. The lat- 50

ter adaptation is shown in elevation in Fig. 2 and hereinafter described.

To use my device as a ground seat it is only necessary to swing the supporting arms 12, which are pivotally fastened to the side members 11, backwardly, and rest their lower extremities 17 upon the ground. By varying the position of the arms 12, the back of the seat may be adjusted to any desired inclination to suit the individual 10 user. When being used on the beach or on sandy or soft soil, the hook-shaped forward ends 13 of the base members 10 may be pressed into the ground 38 as shown in Fig. 2 and serves as anchors. Likewise the lower ends 17 of the arms 15 12 should be pushed into the ground 38 to hold them in place.

As a ground seat my device has numerous valuable advantages, including comfort, cleanliness, protection from the damp ground and many 20 others.

The ease with which my portable seat may be set up, and taken down and folded together, render it invaluable to spectators at outdoor events. When folded, the seat occupies a minimum of 25 space and may be easily carried about from place to place. To fold the seat, the user need only unfasten the attachment 24 and fold the bars 26 and 28 downward and together. This also per-

mits the two sides of the seat to be moved together, and then it is only necessary to unfasten the supporting arms 12 from the rings 16 and swing the members 10 and 12 about their pivots 15 and 19 respectively until they are substantially parallel to the members 11. The protruding fabric pieces 26 and 28 may then be neatly rolled around the members 10, 11, 12, 26, and 28 and the seat is in compact form for carrying.

Although I have herein disclosed a certain embodiment of the invention, it will be understood that various modifications may be employed, without violating the spirit of the invention, all of which are intended to be within the scope of the appended claim.

Having described my invention, what I claim and desire to secure by Letters Patent is:

In a legless seat including a back rest and a seat portion pivoted to each other, the combination of side arms pivoted at one end to the side members of said back rest and provided at the other end with hooks adapted to engage means comprising balls pivoted to said seat portion, and a cross member of hinged sections pivoted at either end to said side members, said hinged sections having means to lock them in horizontal alignment.

WILLIAM E. FLANDERS.
